INTERNAL-COMBUSTION ENGINE.

1,355,615.

Specification of Letters Patent.

Patented Oct. 12, 1920.

Application filed February 1, 1919. Serial No. 274,480.

To all whom it may concern:

Be it known that I, WILLIAM HENRY MARTYN, a subject of the King of Great Britain and Ireland, residing at Tenterfield, 5 New South Wales, Australia, have invented new and useful Improvements in Internal-Combustion Engines, of which the following is a specification.

This invention will generally be used with 10 internal combustion engines operated by gas, particularly "producer" gas.

The cylinders are arranged in twin pairs, with trunk pistons, the combustion ends of the cylinders being nearest the crank shaft, 15 the outer ends of the cylinders being used for pumping the contained fluids.

One twin cylinder will inhale air, the other twin cylinder will inhale a suitable combustible fluid, or gas, preferably, "producer" gas. Each intake will be provided with a suitable check valve to prevent exhalation of the fluid inhaled.

The combustible fluid or gas will, generally, be supplied to the engine through a 20 hollow crank shaft and conveyed thence by a pipe to that part of the combustible fluid or gas cylinder which acts as a pump, in a manner that is well understood.

Each cylinder will be provided with a 25 transfer passage connecting the pumping part of that cylinder with the central or combustion part of the same cylinder, suitable ports being provided in the wall of the cylinder which will be covered or uncovered by the movements of the trunk piston.

The pumping part of each cylinder will 30 be connected by an oblique pipe with the central or combustion part of the twin cylinder, suitable ports being provided which will be covered or uncovered by the movements of the piston.

The intake of the combustible fluid or gas to the air pumping cylinder, must be above 35 the intake of air at or near the center of that cylinder, and the intake of air to the combustible fluid or gas pumping cylinder must be below the intake of combustible fluid or gas at or near the center of such cylinder.

40 But in order that the invention may be properly understood, reference will be made to the accompanying sheets of drawings, in which:—

Figure I is a front elevation of a pair of

twin cylinders, particularly showing the disposition of the oblique pipes which connect the pumping part of each cylinder with the central or combustion part of its twin. 55

Fig. II is a vertical section of the combustible fluid or gas pumping cylinder, the trunk piston being removed.

Fig. III is a transverse section of the same on the line A—A of Fig. II.

Fig. IV is a transverse section on the line B—B of Fig. II. 65

Fig. V is a vertical section of the air pumping cylinder, the trunk piston being removed.

Fig. VI is a transverse section of the same on the line C—C of Fig. V. 70

Fig. VII is a vertical section of the air pumping cylinder, taken on a line at right angles to that shown in Fig. V.

Fig. VIII is a transverse section of the same on the line D—D of Fig. VII. 75

Fig. IX is a diagram illustrating the internal development of the ports in the wall of one of the cylinders at or near its central part at the outer end of the combustion chamber. 80

The combustible fluid or gas pumping cylinder 1, is a twin with the air pumping cylinder 2, the combustion ends of the cylinders being shown at 3, the pumping ends being shown at 4. The combustion ends of the cylinders are inclosed within water jackets 5, which are adjacent the crank shaft. In the diagram Fig. IX, the ports marked 6 are the air ports, the ports marked 7 are the combustible fluid ports and the ports marked 8 are the exhaust ports. The exhaust ports may be provided with a strengthening bridge, as shown in the drawings, owing to their length, but such bridge is not absolutely necessary. Each cylinder 95 is provided, near its central part, *i. e.* the outer end of the combustion chamber, with similar ports 6, 7, and 8.

Each cylinder is provided with a transfer passage whereby the fluid above the piston 100 may escape when it is compressed by the upward movement of the piston, and the ports connecting with the transfer passages are uncovered. The transfer passage 9, pertaining to the gas cylinder 1 should be 105 slightly shorter than the transfer passage pertaining to the air pumping cylinder 2.

When a piston (which is not shown in

the drawings) is at its lowest point, *i. e.* nearest the crank shaft, all the ports situated near the central part of the cylinder will be covered by the aprons of the trunk pistons, but the ports situated near the outer ends of the cylinders will be fully uncovered. The inlet ports, whether for gas or for air, will be provided with back pressure valves which will automatically close immediately 10 the pistons begin to rise.

On a piston rising, the fluid or fluids above it will be progressively compressed and will endeavor to escape through the ports situated near the outer ends of the cylinders; 15 but, as the piston, during its upward movement, uncovers no port near the central part of the cylinder, until it approaches the end of its outward stroke, the compressed fluids cannot escape from the passages into which 20 they have been forced. When the piston nears the end of its outward stroke, the exhaust ports will be the first to be partly uncovered, then, successively, the air ports and the gas ports. There are two series of air 25 ports in the air cylinder 2, *viz*: the ports 11 establishing central communication between the pumping part of cylinder 2 and the transfer passage 10, and the series of ports 6 establishing communication between the 30 outer end of the cylinder 2 and the central part of the gas cylinder 1, through the oblique pipe 12, shown in Fig. I.

There are two series of gas ports in the gas cylinder 1, the ports 13, establishing 35 communication between the pumping part of cylinder 1 and the transfer passage 9, and the series of ports 7, establishing communication between the outer end of the gas cylinder 1, through the 40 air cylinder 2, and the central part of the air cylinder 2, through the oblique pipe 14, shown in Fig. I.

The air ports near the outer end of the air cylinder 2 leading into the transfer passage 10 are marked 11^a, and the gas ports 45 near the outer end of the gas cylinder 1, leading into the transfer passage 9, are marked 13^a.

It will now be possible to describe the cycle of operations. Assuming the pistons to be 50 at the outer ends of their strokes, *i. e.* at a point the most remote from the crank shaft, the inner movement of a piston will, in the case of No. 1, or the gas cylinder, draw a supply of combustible fluid or gas, 55 from any suitable source, into the cylinder above the piston, through the connection 15, that is provided with an inwardly opening valve 16. The piston in the air cylinder 2 will draw a supply of atmospheric air into 60 the cylinder, above the piston, through the connection 17, that is provided with an inwardly opening check valve 18.

A piston having completed its inward stroke, *i. e.* reached a point in the cylinder 65 nearest the crank shaft, the space above the

piston will have been filled, in the case of cylinder No. 1, with the selected combustible fluid or gas, and the space above the piston, in the case of cylinder No. 2, will have been filled with atmospheric air. While the pistons are moving inward toward the crank shaft, they will be compressing a previously admitted charge consisting of a mixture of gas and air, below them, ready for ignition. The compressed charge of mixed gas and 70 air will then be fired, forcing the pistons outward and, incidentally, compressing the fluids above them. This will have the effect of forcing the compressed fluid, in the case of No. 1 cylinder, through the ports 13^a into 75 the transfer passage 9, and through the ports 7 into the oblique pipe 14. In the case of No. 2 cylinder, the compressed air will be forced through the ports 11^a into the transfer passage 10, and through the ports 80 6 into the oblique pipe 12. The pistons continuing to rise, the exhaust ports 8 will be first partially uncovered, thus reducing the pressure from below and getting rid of part 85 of the spent charge. The air ports 11 will 90 then be uncovered, permitting the compressed air within the transfer passage 10 to escape into the inner, or combustion, end of cylinder 2 and scour that cylinder below the piston, the excess of compressed scavenging 95 air, with a part of the spent charge, escaping through the exhaust ports 8. Simultaneously, the air confined within the oblique pipe 12 will enter the central or combustion part of the gas cylinder 1, with a precisely 100 analogous effect, *viz*: scavenging the combustion part of that cylinder of part of the spent charge.

Dealing now with cylinder 1, the compressed gas above the piston will be forced 105 through the ports 13^a into the transfer passage 9, and through the ports 7 into the oblique pipe 14. The piston continuing to rise, the exhaust ports 8 will be first partially uncovered, thus getting rid of part of 110 the spent charge, the remainder of the spent charge being scoured out of cylinder 1 by the compressed air from cylinder 2 being conveyed to cylinder 1 through the oblique pipe 12, as above explained. The air ports 11^a (cylinder 2) and 6 (cylinder 1) being 115 below the level of the gas ports 13 (cylinder 1), the scavenging will take place before the gas can enter either cylinder. The piston continuing to rise, the gas ports 13 (cylinder 1) and 7 (cylinder 2) will become uncovered, admitting the gas through the ports 13 to below the piston in cylinder 1, and through the ports 7, by way of the oblique pipe 14, to below the piston in cylinder 2, 120 thus supplying another charge ready for compression; and the cycle of operations 125 may then be repeated, as above explained.

In the case of ignition failing in either cylinder, a small pipe 20, Fig. I, will be pro- 130

vided to connect the combustion chambers of the two cylinders together, so that there shall be an equalization of pressure, or, it is possible the charge may be ignited through 5 the connection.

Having now particularly described my invention, what I claim is:—

An internal combustion engine comprising a pair of cylinders having separate and 10 independent firing chambers at one end thereof, one of said cylinders having a gas compression chamber at its other end, the other cylinder having an air compression chamber at its other end, admission means

for the gas and air, a port connection between the air compression chamber and an intermediate part of both of the cylinders, a port connection between the gas compression chamber and an intermediate part of both of the cylinders, exhaust ports at the 15 intermediate parts of the cylinders, and pistons in the cylinders connected for synchronous movement and adapted on the power stroke to uncover the air, gas and exhaust ports. 20

In testimony whereof I have signed my name to this specification.

WILLIAM HENRY MARTYN.
